CLAIM

The ornamental design for a fish lure body, as shown and described.

DESCRIPTION

FIG. 1 is a side elevational view of a fish lure body showing my new design, all sides of the body being identical;
 FIG. 2 is a front elevation view of the fish lure body;
 FIG. 3 is a rear elevation thereof;
 FIG. 4 is an elevational view of an alternative form of fish lure body showing my new design;
 FIG. 5 is a front elevation thereof; and,
 FIG. 6 is a rear elevation view thereof.
